GUN MOUNT

George H. Rarey, United States Army, Camp
Holabird, Md.

Application September 11, 1936, Serial No. 100,305

1 Claim. (Cl. 224—29)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gun mount.

The purpose of the invention is to provide a simple and efficient gun mount which may be readily applied to a vehicle in a position to have a wide range of movement in traverse and in 10 elevation and be especially adapted for maneuvering against aerial targets.

To these and other ends, the invention consists in the construction, arrangement and combination of elements described hereinafter and 15 pointed out in the claim forming a part of this specification.

A practical embodiment of the invention is illustrated in the accompanying drawing, wherein:

20 Fig. 1 is a view in side elevation of the front end of a vehicle equipped with the improved gun mount.

Fig. 2 is a view in front elevation with the gun mount in a different position.

25 Fig. 3 is a plan view of the mount independently of its support.

Fig. 4 is a view in elevation thereof.

Fig. 5 is an enlarged sectional view of the mount on the line 5—5 of Fig. 4 but showing its attachment to the support which is in elevation.

30 Figs. 6 and 7 are sectional views on the corresponding lines of Fig. 4.

Referring to the drawing by characters of reference, there is shown a standard commercial truck 35 5 which is provided with a pedestal 6 for carrying a spare wheel or tire. This pedestal is employed to carry the gun mount which comprises a standard in the form of a tube 7 having a flat plate 8 which is attached to the pedestal by the three bolts 9 provided for attaching the spare wheel. The plate 8 is additionally supported by a 40 forwardly extending brace 10 bolted to the front part of the vehicle frame 11 and by a laterally extending brace 12 which passes through an opening 13 in the hood and in rear of the motor 45

and is bolted to the vehicle frame 11. The lower end of the tube 7 carries a spacer block 14 fitting against the pedestal 6 and is further held thereto by a clip consisting of a U-bolt 15 and a plate 16.

Bushings 17 and 18 fixed respectively in the 5 upper and lower ends of the tube 7 rotatably mount a pintle 19 which projects from the tube. An arm 20 fixed on the upper end of the pintle has its outer end connected to the lower end of the pintle by a brace 21. A yoke 22 is rotatably 10 mounted on the outer end of the arm by means of a bolt 23 which passes through the yoke and arm and has a nut 24 on its lower end confining a washer 25 against the arm. The yoke is formed with two sets of aligned apertures 26 and 27 for 15 alternate reception of a trunnion pin 28 on which a machine gun 29 is mounted. The inner portion of the arm 20 is supported on a bracket 30 which is fixed to the tube 7 and is provided with an arcuate slot 31. A bolt 32 carried by the arm 20 extends through the slot and receives a clamping handle 33 which may be turned into engagement with the bracket to securely hold the arm in position of adjustment.

While the gun arm is only capable of being 25 swung through about 180 degrees, the free mounting of the yoke 22 permits of all-around firing. When the gun is to be employed against aerial targets, the arm is generally swung to the position shown in Fig. 2.

30 I claim.

In combination with a vehicle and a support thereon, a gun mount comprising a standard fixed to the support, braces between the standard and the vehicle, a pintle mounted in the standard, an 35 arm fixed to the upper end of the pintle, a brace connecting the outer end of the arm and the lower end of the pintle, a bracket on the standard for supporting the inner part of the arm said bracket formed with an arcuate slot, a clamp carried 40 by the arm and riding in the slot of the bracket, and a gun-carrying yoke rotatably mounted in the outer end of the arm.

GEORGE H. RAREY. 45
